LUKE H. ROONEY, OF NEW BEDFORD, MASSACHUSETTS, ASSIGNOR TO THE WHITIN MACHINE WORKS, OF WHITINSVILLE, MASSACHUSETTS, A CORPORATION OF MASSACHUSETTS.

RING-FRAME TOOL.

1,139,806.

Specification of Letters Patent.

Patented May 18, 1915.

Application filed October 22, 1912. Serial No. 727,161.

To all whom it may concern:

Be it known that I, LUKE H. ROONEY, a citizen of the United States, residing in New Bedford, Massachusetts, have invented the 5 following described new and useful Ring-Frame Tool.

The invention is a tool for removing the travelers from spinning rings and is designed to obviate the trouble and waste of 10 time ordinarily experienced by the operative in prying or pulling the traveler off of the ring when it is necessary to remove it. The new tool operates by pressing the traveler against the ring itself and relies on the high 15 temper of the traveler to cause it to snap into pieces when distorted or flattened against the top or side of the ring. The tool comprises a part adapted to find a bearing on some solid part of the machine, and preferably upon the lower side of the ring rail itself, and another part adapted to overlie the spinning ring in a position from which it can be moved to press the traveler downwardly against the top of the ring and there- 20 by snap it in two. Such an instrument is shown in preferred and modified forms in the accompanying sheet of drawings, where- 25 in—

Figure 1 is a perspective view of the tool 30 in use, showing the ring rail and ring in section, and the traveler in dotted lines; Fig. 2 is a modified form of the same instrument, incorporating certain adjustments.

As will be seen from the drawings, the 35 tool comprises a handle 1, to which the parts 2 and 3 forming the fulcrum member and the traveler-engaging member, respectively, are secured by means of a screw 4, shown in dotted lines in Fig. 1. In this form, the 40 said members 2 and 3 can be most conveniently made in one piece by striking them up from a blank of strap iron, forming the connecting part 5, with a hole to receive the set screw, or otherwise, whereby it can be 45 screwed to the handle. The lower member 2 is preferably adapted to engage upon the under side of the front flange 6 of the ring- 50 rail 7, and for this purpose is provided with a shoulder 2^a, as indicated, which will hook on to the back edge of this flange in an obvious manner. The upper member 3, which 55 may be parallel with the lower member, is also somewhat longer, depending upon the

position of the ring 8 with reference to the front of the ring rail, so that it will overlie 55 the ring when in the position indicated in the drawing. The length of the back portion 5 is selected according to the depth of the particular rail flange and the height of the ring, so that in the said position it will 60 be close to the top of the ring. The traveler 9 is brought to the front of the ring, and by swinging the tool on the shoulder 2^a as a fulcrum, the member 3 will be forced downwardly and will break the traveler against 65 the ring. The broken pieces will snap off to one side or the other and fall on the floor.

In the modified form shown in Fig. 2, the upper and lower members 3 and 2 are arranged to be relatively adjustable with respect to each other, so as to be thereby accommodated to different types or thicknesses of ring-rails and rings. The lower member 2, provided with the same shoulder 2^a is in this form an L-shaped piece bored with a 75 hole to receive the handle screw 4. Between the back of this member and the end of the handle, an auxiliary back plate 10 is inserted, this plate being adapted to be adjustably clamped between the handle and the member 80 2 and having an oblong slot receiving the screw 4 for this purpose. The said plate has a rearwardly turned flange 11, and the top member 3 is adjustably secured to it by means of a clamp screw 12 passed through 85 an oblong slot in the top member and threaded in the flange. By means of the two screws it will be evident that the traveler-engaging member can be brought to any position necessary to enable it to reach and 90 overlie the spinning ring regardless of the depth of the rail flange or the distance of the ring therefrom.

It will be understood that the tool above described and herein claimed is capable of 95 embodiment in other and dissimilar forms and that within the scope of the claim various other means of rendering the parts of the tool adjustable can be resorted to.

I claim:

A tool for crushing travelers upon spinning rings, comprising a handle, an upper longer part projecting therefrom and adapted to cover a portion of the ring a lower shorter part opposed to the upper part and 105 projecting from the handle in the same di-

rection, and an upward projecting shoulder on said lower part, the handle side of which shoulder serves as a fulcrum bearing upon the support of the spinning ring, whereby the upward movement of the handle serves to press the said upper part against the ring.

In testimony whereof, I have signed this

specification in the presence of two witnesses.

LUKE H. ROONEY. [L.S.]
